UNITED STATES PATENT OFFICE

HENRY W. O'DOWD, OF JERSEY CITY, NEW JERSEY, ASSIGNOR TO STANDARD GAS EQUIPMENT CORPORATION, A CORPORATION OF MARYLAND

DESIGN FOR A GAS STOVE CASING

Application filed April 23, 1931. Serial No. 39,599. Term of patent 14 years.

To all whom it may concern:

Be it known that I, HENRY W. O'Dowd, a citizen of the United States, residing at Jersey City, in the county of Hudson and State of New Jersey, have invented a new, original, and ornamental Design for Gas Stove Casings, of which the following is a specification, reference being had to the accompanying drawings, forming a part thereof, and in which—

Fig. 1 is a perspective view showing the gas stove casing in closed position; and

Fig. 2 is a perspective view showing the casing in opened position.

I claim:

The ornamental design for a gas stove casing substantially as shown.

In testimony whereof, I have affixed my signature hereto.

HENRY W. O'DOWD.
